UNITED STATES PATENT OFFICE.

ALBERT KREHLIK, OF NEWBURGH CITY, OHIO.

CARPENTER'S GAGE AND SCRIBER.

No. 907,612.

Specification of Letters Patent.

Patented Dec. 22, 1908.

Application filed June 13, 1908. Serial No. 438,329.

To all whom it may concern:

Be it known that I, ALBERT KREHLIK, a citizen of the United States, residing at Newburgh City, in the county of Cuyahoga and State of Ohio, have invented certain new and useful Improvements in Carpenters' Gages and Scribes, of which the following is a specification.

My invention relates to improvements in carpenters' gages and scribes, the invention being adapted for use either as an ordinary carpenter's gage or as a scribe, the primary object being to provide a generally-improved device of this class which will be exceedingly simple in construction, cheap of manufacture, and efficient in use.

With these ends in view, the invention consists in the novel construction, arrangement, and combination of parts, hereinafter described, illustrated in the accompanying drawings and particularly pointed out in the appended claims.

Referring to the drawings, forming a part of this specification, Figure 1, is a side elevation of the improved tool. Fig. 2, a sectional view, the scale-bar being removed from the gage-stock and an ordinary lead pencil substituted, thus adapting the same for use as a scribe. Fig. 3, a view of the front or face portion of the improved gage-stock. Fig. 4, a top plan view of the same. Fig. 5, a detailed perspective view of the improved pivotally and adjustably-mounted scribe member detached.

Similar numerals of reference designate like parts throughout all the figures of the drawings.

The gage-stock comprises longitudinal-extending base-members or walls 1, connected by means of an intermediate head-block or casing 2. The base-members or walls 1, are provided at each end with heads 3, and 4, terminating in guide-lugs 5, provided with bearing-openings 6, adapted to receive and carry the graduated scale-bar 7. The scale-bar is provided at one end with a rotatable marker-disk 8, said marker-disk being carried upon a bearing-screw 9, threaded into the end of the scale-bar 7. The head 3, forms the face or guard-head of the gage-stock, and the scale bar 7, is adjustably-mounted and carried within the bearing-openings 6, of the guide-lugs 5, by means of a pair of spring-resistant clutch members 10, pivotally-mounted and interposed at their lower or base ends

between the base-members or walls 1, by means of bearing bars or pins 11, which take through bearing-openings in bearing-lugs 12, of the clutch members.

The clutch-members 10, are provided with friction-clutch-openings 13, registering and in alinement with the bearing-openings 6, of the guide-lugs, and adapted to receive and adjustably contain the graduated scale-bar 7, carried within said openings 6, of the guide-lugs 5. The free or handle ends of the clutch-members 10, are arranged on each side of the head block or casing 2, and project beyond the same, said clutch-members being held in their engaging position with the scale-bar 7, by means of a coil-spring 14, surrounding said scale-bar and interposed between said clutch-members, said coil-spring being also housed within the head-block or casing 2.

As a means for adapting the improved tool for use as a scribe, the head 4, is provided with an arm 15, terminating in a bearing-lug carrying a pivotally and adjustably mounted scribe member 17. The scribe member 17, comprises a single blank of metal longitudinally bent upon itself forming the base wings or bearing-lugs 17^a. The scribe member 17, is adjustably-secured to the bearing-lug 16, by having its bearing-lugs 17^a, secured thereto by means of a screw 18, the shank of which passes through the openings of the bearing-lugs 16 and 17^a, said screw 18, being drawn up or tightened by means of a thumb-nut 19. The shank of the screw 18, is preferably provided near the head of the screw with a short rib which is adapted to fit within a recess 20, (see Fig. 5) extending from the bearing-opening of one of the bearing-lugs 17^a.

The scale-bar is removed by drawing the free or handle ends of the clutch-members 10, towards each other and into engagement with the intermediate head-block or casing 2, said casing 2, acting as a stop for maintaining the clutch-members 10, in a substantially parallel position with each other in their released position while the scale-bar is being removed. After the scale-bar has been removed a pencil 21, may be inserted, and secured in proper position by releasing the clutch-members, thus adapting the instrument for use as a scribe as illustrated in Fig. 2, of the drawings.

From the foregoing description, taken in

connection with the accompanying drawings, the operation and advantages of my invention will be readily understood.

What I claim and desire to secure by Letters Patent, is:

1. A gage and scribe, comprising a gage-stock casing provided with heads terminating in guide-lugs having openings, a pair of spring-resisted pivotally-mounted clutch members carried by said gage-stock casing intermediate said guide-lugs and provided with openings in alignment with said openings of said lugs, one of said heads being provided with an arm terminating in a bearing-lug, a scribe member pivotally mounted in said bearing-lug, and a bar carried in said openings of said lugs and clutch members.

2. In a gage, a gage-stock comprising base-members connected by a casing and heads terminating in guide-lugs having openings on each side of said casing, clutch-members pivotally-mounted on each side of said casing, and interposed between said base-members, said clutch-members being provided

with friction-clutch-openings adapted to register with said openings of said guide-lugs, a coil spring mounted within said casing and interposed between said clutch members, and a scale-bar mounted within said openings of said clutch-members and said guide-lugs.

3. A gage and scribe, consisting of a gage-stock comprising a casing provided with heads terminating in guide-lugs having openings on each side of said casing, spring-resisted clutch-members pivotally-mounted intermediate said heads and provided with friction-clutch-openings in alignment with said openings of said guide-lugs, a bar mounted in said guide-lug and friction-clutch openings, and a scribe member pivotally secured to one of said heads.

In testimony whereof I have affixed my signature, in presence of two witnesses.

ALBERT KREHLIK.
